UNITED STATES PATENT OFFICE.

NORMAN HUBBARD, OF ELIZABETH, NEW JERSEY, ASSIGNOR OF ONE-HALF TO PEREZ
M. STEWART, OF NEW YORK, N. Y.

WATER-HEATER.

1,349,571.

Specification of Letters Patent. Patented Aug. 17, 1920.

Application filed June 30, 1917. Serial No. 177,949.

To all whom it may concern:

Be it known that I, NORMAN HUBBARD, a citizen of the United States, residing at Elizabeth, county of Union, and State of New Jersey, have invented certain new and useful Improvements in Water-Heaters, of which the following is a specification.

My invention relates in general to water heaters, that is to say, apparatus for raising the temperature of water, whether for the purpose of simple heating or for the generation of steam. More specifically, the invention concerns water heaters of the type in which a gas flame is employed as the heating medium.

Apparatus of this class may be employed for example to produce hot water for ordinary household purposes, or for producing hot water for use in heating systems. It will, however, be understood that the apparatus itself which forms the subject matter of the present invention, might, if desired, be employed for heating other liquids. Among the objects of the invention, I may mention the purpose to provide a water heater of high efficiency and of simple design or construction. Other objects are for example to produce a water heater of convenient size and form for household use and one which can be readily connected with the gas and water supply systems already present. The invention is illustrated by way of example in the accompanying drawing, in which,

Figure 1 is a central vertical section through a water heating unit, constructed according to my invention,

Fig. 2 is a horizontal section thereof taken on the line II—II of Fig. 1, and

Fig. 3 is a similar section taken on the line III—III of Fig. 1.

The embodiment herein shown is designed so as to be readily connected with the gas and water pipes, involving but one gas inlet and single water inlet and outlet connections. As clearly shown in Fig. 1, the apparatus is grouped within a cylindrical housing 10 of, for example, metal tubing or sheet metal, lined with suitable heat insulating material 11, as for example asbestos packing. The housing cylinder is mounted between heads 12 and 13, the water inlet pipe 14 extending axially through the head

12 while the water outlet pipe 15 extends axially out through the head 13. It will be understood that the unit comprises a water system and a gas system so associated that during passage of the water through the unit, it is exposed to the high temperature of burning gas, the low temperature water entering through pipe 14 and the heated water passing out through the pipe 15. The water system comprises, in addition to the inlet and outlet pipes 14 and 15, lower and upper headers 16 and 17 with which the pipes 14 and 15 are suitably connected and between which are disposed in the present instance, three water tubes 18 of for example, drawn sheet metal. Concentrically disposed within each of the tubes 18 is a fire tube 19, which extends across the water space in each header for the purpose of maintaining the water within each of the tubes 18 in the form of an annular body. Tube 19 in each instance is threaded at either end, one end being screwed into tapped hole in bottom of lower header 16; upon the free end of tube 19 is screwed a bushing 20 having a conical outer surface fitting within a similarly formed orifice in the top of upper header 17. The ends of tubes 18 are in each instance fitted into conical orifices in the top and bottom of lower and upper headers respectively.

The headers 16 and 17, together with the tubes 18 and 19, are firmly secured in their assembled position by turning the conical bushings 20 in the proper direction, both ends of fire tubes 19 being threaded in the same direction, (see Fig. 1), so that the two headers are given a tendency to move in opposite directions on the fire tubes, against the resistance offered by the engagement of the conical ends of the water tubes in their respective seats. In this way a firm water tight engagement of the various joints is secured.

Referring to Figs. 1 and 2, it will be clearly seen that the three tubes 18 are distributed uniformly around the main axis of the unit and that the header 16 which receives the incoming water from the single axial inlet pipe, distributes the water to the three rising tubes from which the three bodies of heated water are again united in the header 17 prior to discharge through the

outlet pipe 15 as a single body of heated water. This sub-division of the water body is illustrated in the present example as being a division into three parts, but it must be understood clearly that any suitable number of divisions may be effected in accordance with the particular requirements involved, the purpose being to augment the surface exposure of the water to the reception of heat from the heating medium.

The gas system of the unit is somewhat similarly subdivided from the common source so as to provide a plurality of individual gas flames or burners for the introduction of heat into the water sub-divisions. The single gas inlet is represented at the pipe 21 as connecting with an air-mixing element 22 of well known construction, from which the combustible mixture of the air and gas passes through pipe 23 into two sets of burners, each of which is sub-divided into individual burners for the respective water sub-divisions. The upper set of burners receives its mixture of gas and air through the rising pipe 24 from which it is distributed through the annular burners 25 disposed above the header 16 surrounding respectively the three water tubes 18 so as to apply heat to the outer surface of the annular column in each of said tubes. The lower set of burners likewise receive their mixture of gas and air from pipe 23 and are distributed uniformly around the main axis of the unit, one burner or outlet 26 being provided in axial position immediately beneath each of the inner tubes 19. The flames from burners 26 are directed upwardly into the inner tubes 19 where they encounter in each case a helical deflector 27 which throws the flame outwardly against the inner wall of tube 19. These helical deflectors 27 are constructed for example in the form of castings or twisted sheet metal strips which fit snugly within the tubes 19 and are provided at the top with lateral ears 28 which rest upon the top of the bushings 20 to maintain them in proper position with their lower ends a short distance above the bottom of the fire tubes. The deflectors not only spread the flame centrifugally outward against the inner wall of tubes 19, but they likewise prolong the travel of the flame through the tubes and form heat conductors which transfer heat into the tubes 19 so that a highly efficient delivery of the heat units contained in the fuel is made possible.

The products of combustion from the inner and outer burners are discharged through the common outlet 29. In order to retard the exit of heated gases from the outside burners 25, a metal baffle plate or diaphragm 30 is disposed in the upper portion of the unit and extends to within a short distance of the inner wall of the cylindrical

housing, so that an efficient heating chamber is maintained within the space inclosed by the housing.

With the construction above described, it will be clear that not only is the water sub-divided into a plurality of individual bodies for the reception of heat, but these individual bodies are in the form of annular columns to which the heat is applied at both the interior and exterior surfaces. The proportionate surface area to the total volume may in this way be made very great and suitable proportioning of diameters of the tubes 18 and 19, together with the proper selection of the number and length of subdivisions employed, will adapt the device to meet a wide range of requirements as to rapidity and capacity of heating.

The provision of conical seats for the connection of the tubes with the headers, while being shown in the preferred form, is to be understood as merely illustrative of a construction in which the orifices and the ends of the tubes are tapered or flared in one direction or the other, so that relative movement of the two headers toward or away from each other, as the case may be, will have the effect of bringing the adjacent surfaces of the tubes and headers into firm water-tight contact.

I claim:—

1. A water heater comprising in combination, a water inlet below and a water outlet above, means for sub-dividing the water on its way from inlet to outlet into a plurality of upright annular columns, means for locally producing a heating flame within the lower portion of the space inclosed by each of said annular columns, and an annular burner surrounding the lower portion of each annular column for locally producing a ring of heating flame in proximity to the outer surface thereof.

2. A water heater comprising in combination a water inlet below and a water outlet above, means for sub-dividing the water on its way from inlet to outlet into a plurality of upright annular columns, an axially disposed burner below each of said annular columns for delivering a local flame into the lower portion of the interior space inclosed by each of said annular columns of water and a circumferentially disposed annular burner at a somewhat higher elevation surrounding the lower portion of each of said annular columns of water for delivering a local ring of flame in proximity to the outer surface of each of said annular columns of water.

3. A water heater comprising in combination, horizontally disposed upper and lower headers, upright water tubes operatively connecting the same, fire tubes passing through said water tubes and headers, an axially disposed burner below each of said

fire tubes for delivering a local flame into the lower portion thereof, and a circumferentially disposed annular burner above the lower header and surrounding each water tube for delivering a local upwardly directed ring of flame in proximity thereto.

4. A water heater comprising in combination an upright fire tube, means for main-

taining a supply of water around said fire tube, an axially disposed burner for delivering a local upwardly directed flame into the lower portion of said fire tube, and a helical deflector disposed within said fire tube and terminating at a short distance above the lower end of the fire tube.

NORMAN HUBBARD.
